UNITED STATES PATENT OFFICE.

FELTON M. LYTHE, OF BOSTON, MASSACHUSETTS.

LAMP-WICK.

SPECIFICATION forming part of Letters Patent No. 373,935, dated November 29, 1887.

Application filed January 8, 1887. Serial No. 223,760. (No model.)

To all whom it may concern:

Be it known that I, FELTON M. LYTHE, of Boston, in the county of Suffolk and State of Massachusetts, have invented certain new and 5 useful Improvements in Lamp-Wicks, of which the following is a specification.

My present invention has for its object to provide an improved wick for burning oils which shall be much less combustible than other wicks, but, by reason of its peculiarities, resemble the ordinary cotton wick as nearly as possible in the manner in which the oil is supplied and consumed at the point of ignition.

It is well known that the tip of an ordinary 15 cotton wick does not materially consume after the heat has charred or carbonized its fiber, but serves as an uninflammable tip to the wick from which the flame rises; but this carbonized portion, having little stability and firmness, 20 falls away, and, further, the wick must be frequently trimmed from time to time to make an even and steady flame, even for a short time.

Now, my present invention consists in an 25 improved wick for use in lamps, composed of porous carbon, which not only presents a burning-surface for the flame of precisely the same material that is formed naturally in the use of an ordinary cotton wick, thus making 30 probably the best support for the flame, but also one that is stable and can be used without material consumption, and consequently needs no trimming to keep its flame-supporting surface even and constant.

35 It further consists in the combination, with an ordinary cotton wick, of a burning tip of carbon mechanically connected thereto.

In the accompanying drawings, Figure 1 represents a perspective view of a carbon wick 40 embodying my invention. Fig. 2 represents a longitudinal section of the same. Figs. 3, 4, and 5 represent end views, showing different forms. Fig. 6 represents an edge view, showing a carbon tip applied to a fibrous wick. 45 Figs. 7, 8, 9, 10, and 11 represent different forms in which the carbon wick may be formed.

Similar letters of reference in the several figures indicate the same parts.

50 In carrying out my invention I make a wick, *a*, of carbon, preferably of the kind that is made porous or spongy and capillary—that is

to say, having numerous small cells so communicating throughout the length of the wick as to form ducts adapted to convey oil upwardly through the wick by capillary action. Such porous wick may be formed by grinding crude masses of carbon to a very fine powder, 55 agglomerating the powder by means of a syrup or other like material into a stiff paste, pressing the paste in a mold or die into the form of the wick, and finally rendering the molded piece of carbon porous and capillary by submitting it to a high heat with free access of air.

Any other suitable process of making the 60 carbon porous may be adopted; or, if preferred, the wick may be cut or sawed from a mass of carbon that has previously been made porous.

I prefer to supplement or aid the capillary 70 action of the cells in the porous carbon by artificially forming small longitudinal ducts *b b* in the wick by small rods or wires placed in the mold or die which forms the plastic carbon wick, said rods or wires being subsequently removed, leaving the uninterrupted 75 longitudinal passage *b*.

The surfaces of the carbon wick may be provided with narrow grooves *c*, as in Figs. 4, 5, 80 and 10, operating by increasing the surface to cause the oil to pass up in said surfaces by capillary action, and in this case the wick may have the straight internal ducts or passages, 85 as in Fig. 4, or may be formed without them, as in Figs. 5 and 10.

The carbon wick may be of less length than required to conduct the oil from the reservoir to the burner—that is, it may form a practically incombustible constant tip secured mechanically to a fibrous wick, *w*, as in Fig. 6, 90 the lower end of the carbon being provided with the groove in its lower side, formed by the lips *a' a'*, in which the fibrous wick is mounted and in which it is secured in any suitable manner. In the present instance, 95 however, I employ a two-pronged fastener, *f*, similar to an ordinary paper-fastener, inserted through holes formed in the lips *a' a'*, and the ends separated and turned down. I do not desire to be confined, however, to these devices, as the carbon and fibrous wick may be detachably connected by various other means

without departing from the spirit of my invention.

The carbon wick may have an enlargement at its lower end to increase the area immersed in the oil, as in Fig. 7.

The carbon wick may be cylindrical, as shown in Fig. 8, or annular, as in Figs. 9 and 10, for Argand burners.

Fig. 11 shows a form of wick suitable for oil-stoves.

My invention is not limited to porous or spongy carbon, though this is preferred.

The ducts *b b* may be formed in solid or non-porous pieces of carbon as the only means of conducting the oil, or both the ducts *b* and the surface-grooves *c* may be formed in non-porous carbon wicks. The use of porous carbon is much to be preferred, however, as the capillary properties of a wick made thereof are much greater than those of a wick of solid or non-porous carbon having artificially-formed ducts *b*, and the oil also will soak into the tip more, giving a support for the flame.

It will be seen that a carbon wick is much less destructible than other materials, and is not liable to be broken or injured by handling.

Moreover, the wicks can be made very cheaply.

I prefer in using porous carbon to cover the sides of the wick with varnish or other analogous material to form an oil-proof coating, *o*, as in Fig. 3, to prevent the oil from exuding along the sides of the wick in its upward passage.

I claim—

1. As an improved article of manufacture, a lamp-wick of carbon having ducts or channels for the passage of the oil by capillary action, as set forth. 35

2. A lamp-wick composed of porous carbon, as set forth.

3. A lamp-wick composed of carbon having longitudinal ducts or channels *b b*, as set forth. 40

4. A lamp-wick composed of porous carbon having longitudinal ducts or channels *b b*, as set forth. 45

5. The combination, with a carbon tip, of a mechanically-attached fibrous wick, substantially as described.

6. The combination, with a carbon tip, of a wick of fibrous material mechanically attached thereto, substantially as described.

7. A wick of porous carbon having an external oil-proof coating, substantially as described. 50

8. The combination, with a carbon tip having a groove, of a fibrous wick inserted in said groove, and devices for securing the two together, as set forth. 55

In testimony whereof I have signed my name to this specification, in the presence of two subscribing witnesses, this 5th day of January, 1887.

FELTON M. LYTHE.
